UNITED STATES PATENT OFFICE.

SOLOMON GERMAN, OF REISTERSTOWN, MARYLAND.

GARMENT-FASTENER.

1,109,215.

Specification of Letters Patent. Patented Sept. 1, 1914.

Application filed April 21, 1911. Serial No. 622,454.

To all whom it may concern:

Be it known that I, SOLOMON GERMAN, a citizen of the United States, residing at Reisterstown, in the county of Baltimore and State of Maryland, have invented certain new and useful Improvements in Garment-Fasteners, of which the following is a specification.

This invention relates to separable fasteners for gloves and garments and has for its object the improvement of such devices with a view to increasing their utility and rendering their operation more sure and effective for the purposes for which they are designed.

With this object in view the invention consists in the improved construction, arrangement and combination of the parts of a fastener which will be fully described hereinafter and afterward specifically claimed.

In order that the construction and operation of my invention may be readily understood, I have illustrated a preferred embodiment of it in the accompanying drawings, in which—

Figure 1 is a perspective view of the parts of the socket member detached and separated. Fig. 2 is a similar view of the parts of the stud member, and Fig. 3 is a transverse vertical sectional view of both members attached to the two parts of a glove or garment and engaged with each other.

In this description and in the several figures of the drawing, like parts will be referred to, and are indicated by the same reference characters.

Referring specifically to the drawing, 5 indicates the main part of the socket member being in the form, before assembling it with the other parts, of an annular plate 6 having a circular depending flange 7 depending centrally from the material of said plate around its central opening 8. Upon one edge of the plate 6 is hinged a cap 9 of inverted dish form from the center of which depends a plug or teat 10 of substantially conical form with a rounded point 45 and provided with a groove 10' adjacent to the cap 9, forming a shoulder at the upper end of the teat. When this cap is closed down on the plate 6, the plug 10 will project into the center of the opening 8. 50 To secure the socket member to one of the overlapping edges 100 of a glove or

garment, a washer or annular plate 11 of a curved cross sectional form, as shown in Fig. 1, is laid on the under side of the material, as seen in Fig. 3, and the depending flange 7 passed through the material and into the washer 11 where it is secured by clenching or upsetting its lower edge after the manner of an eyelet.

The stud member comprises an annular plate 12 from the center of which rises a stud 13 of a well known construction comprising a number of resilient prongs 14 bent to form a head with a somewhat restricted neck as at 15, the upper ends of the prongs being curved to form, when brought together, the surrounding walls of a central opening 16. To connect this stud member a washer 17, shown in Fig. 2, of substantially the form of the washer 11 of the socket member before described is laid on the under side of the other overlapping edge 200 of the glove or garment as shown in Fig. 3. An annular plate 18 having a depending central flange 19 is laid on top of the material and its flange passed through and upset or turned outward, around the inner edge of the washer 17. The plate 12 is now laid on the plate 18 and an annular binding plate or washer 20 is laid on the plate 12, the outer edges of said washer 20 being upset or turned in around the outer edges of plate 18 firmly securing the plate 12 between said washer and the plate 18 as clearly shown in Fig. 3. The overlapping edges 100 and 200 being separated, and the cap 9 of the socket member raised, the socket member can be brought down over the stud 13, as in the manner usual with stud and socket fasteners, and the resiliency of the prongs 14 of the stud 13 will cause the head portion or stud to expand after passing through the socket which will correspond with the usual engagement of a stud and socket, but by bringing down the cap 9, the plug 10 will enter the opening 16 in the top of the stud, the prongs 14 engaging in the groove 10', and, by virtue of its conical end, will further spread the head of the stud thus firmly securing the flange 7 of the socket member in the neck 15 of the stud member until it is relieved by raising the cap 9 and withdrawing the plug 10, the yielding hold of the resilient force of the prongs of the stud being maintained but which will readily be broken by raising the edge 100 off the

edge of 200 of the glove or garment. It will be observed, that the means for attaching the members to the material prevents their displacement or pulling out, the plates or washers 11 and 17 forming rigid reinforcements around the holes through the material and against which the lower edges of the plates 7 and 19 are clenched. Furthermore, the flange of the stud member 10 is fastened upon the outside of the material and is secured rigidly in place by the binding washer 20 between two metallic surfaces. By this construction both members are firmly secured to the respective overlapping edges of the glove or garment, means are provided for making a preliminary yielding connection between the two edges, and for positively locking the two members together until released by raising the cap, and further means for rigidly locking the cap to said stud member, to prevent movement of the cap only when a positive pull is exerted thereon.

While I have specifically described the construction of the several parts composing my improved fastener, I desire it to be understood that changes and variations therefrom may be made without departing from the spirit and scope of the invention.

Having thus fully described my invention, what I claim as new and desire to secure by Letters Patent of the United States, is

In a separable fastener, a stud member

comprising a series of resilient prongs rising from a plate forming a head, a socket member forming an eyelet to be engaged by said stud member, the head of said stud member being normally greater in diameter than said eyelet member, whereby a snap fastening is secured between the two members, and means for spreading said head and locking it positively in said socket member, said spreading means embodying a hinged cap, a conical plug rigidly secured to said hinged cap, and provided with a groove in its base at its connection with said cap, said groove forming an abrupt shoulder to engage the ends of the resilient prongs and lock the parts together against other than a positive displacement, the diameter of the grooved portion of the plug being greater than the width of the opening formed between the ends of the resilient prongs, whereby when the ends of the prongs are seated in the groove of the plug, the prongs will be expanded and be held positively in contact with the socket member and retain the members rigidly together, it is now desired to

In testimony whereof I affix my signature to

SOLOMON GERMAN.
